CLAIM

The ornamental design for a case for electronic communication device, as shown and described.

DESCRIPTION

FIG. 1 is a front, left, and top perspective view of a case for electronic communication device showing my new design; FIG. 2 is a rear, right, and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is an enlarged view of portion 9 shown in FIG. 1; FIG. 10 is an enlarged view of portion 10 shown in FIG. 2; FIG. 11 is an enlarged view of portion 11 shown in FIG. 3; and, FIG. 12 is an exploded front, left and top perspective view thereof.

The dash-dash broken lines in the drawings depict portions of the case for electronic communication device that form no part of the claimed design. The dot-dash broken lines in the drawings represent boundaries of the enlarged portion shown in FIGS. 1, 2, 3, 9, 10, and 11 that form no part of the claimed design.

1 Claim, 12 Drawing Sheets
